SOUNDING DEVICE

Application filed May 23, 1928. Serial No. 279,902.

This invention relates to a sounding device, and particularly to one which is adapted for producing articulated sound, such as the word ma-ma or the like, the device being intended essentially for use in dolls and similar toys.

An object of the present improvement is to provide a sound producing device of the character referred to and which will include 10 a gravity operable bellows, an element to produce sound in consequence of a gravity operation of the bellows, and a novel form of control means for the emitted sound, which control means is of simple and practical construction and is adapted to perform 15 its sound articulating function independently of the gravity operation of the bellows.

A more specific object is to provide an improved form of control means for the 20 emitted sound which control means comprises a plurality of pivotally mounted discs so weighted and co-related with each other and with the remainder of the mechanism as to cause successive sounding of the sound 25 producing element in a predetermined manner when the doll or other toy is moved from an upright to a reclining position.

A further specific object is to provide a sound producing device of the character indicated including a casing having a partition 30 therein formed with a sound chamber, the latter having a movable closure, to provide a tubular bellows cloth connected with said partition having a freely movable 35 weight connected thereto comprising a gravity movable bellows head, the partition constituting a stationary bellows head and having a reed in its sound chamber in communication with the interior of the bellows so as 40 to be sounded by movement of the movable head, all of said parts being within the casing, and to provide further a control means for the mentioned closure which control means consists of gravity acting mechanism 45 which is independent of the gravity action of the movable bellows head but which occupies a position within the casing extending along one side of the casing substantially parallel with the path of movement of the 50 movable bellows head.

A further specific object is to provide an improved and efficient means for connecting the bellows cloth with the bellows head.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:—

Fig. 1 is a vertical sectional view through a sounding device constructed in accordance with this invention.

Fig. 2 is a similar view but taken at right angles to the view Fig. 1.

Fig. 3 is a similar view but showing the mechanism in its reversed position and the gravity moving parts in their opposite extreme, as compared with the position Figs. 1 and 2, and

Fig. 4 is a view similar to Fig. 3 but showing the gravity moving parts in an intermediate position.

Referring to the drawings for describing in detail the structure which is illustrated therein, the reference character L indicates an enclosing casing or housing within which the operative mechanism is contained. This housing may be of any appropriate shape or construction and may be of either sheet metal, cardboard, or other material. It is preferably, though not necessarily, of cylindrical form including an annular side wall as 1, and opposite end walls as 2 and 3. One of these end walls, as 3, is perforated, as indicated at 4—4, so that the sound may readily pass outwardly from the housing.

Within this housing is a bellows member G mounted in a relatively fixed position extending across the housing and constituting in reality a partition within the housing spaced from the end wall 3 so as to provide a sound defusing chamber as 5 within the housing between itself and said wall 3.

This partition or bellows member may take any appropriate form and may be held in position by any suitable means but for the purpose of the present illustration it is shown to consist of a sheet metal disc as 6 of general annular contour having a marginal flange portion as 7 fitting snugly into the end portion of the housing and being in turn flanged laterally as at 8 to overlie the end edge of the housing, thereby to retain the partition against lateral movement as well as against longitudinal movement within the housing.

The end wall 3 is shown to have a marginal flange as 9 which telescopes over the outer annular surface of the end portion of the housing, and this flange has in-struck portions as 10 which engage the flange 8 for mutual retention both of the partition and of the wall 3 against movement with respect to each other, it being understood that the flange 9 grips fixedly upon the wall of the housing by tight frictional contact, by the use of an adhesive, or otherwise.

Attached to the inner or upper surface of the disc 6 is a disc or member 11 which has a laterally projecting annular flange as 12 thereon serving as the immediate means provided for attachment of the bellows cloth 13.

The members 6 and 11 are so shaped as to provide between them a sound chamber as 14 within which is arranged a reed 15 always in communication with the interior of the bellows as by means of an opening 16 into which is fitted a hollow tubular member 17 having direct connection with one end of the reed.

The outer or lower wall as 18 of the sound chamber is formed with a sound emitting opening as 19 therethrough and this opening is guarded by a movable closure 20.

The closure 20 is pivotally mounted upon the stationary head of the bellows as at 21 and its opening movement is limited by a stop as 22 which is provided for that purpose. At its free edge this closure extends beyond the sound chamber and is shaped to provide a surface as 23 at one end of which is provided a cam-like portion 24 for purposes which will be presently described.

The free end of the bellows cloth is closed by a disc 25 which preferably is of considerable weight and is adapted thereby to constitute a movable gravity actuated bellows head.

The manner of connecting the opposite ends of the bellows cloth 13 with the stationary and movable heads may take any appropriate form. As herein shown it is suggested that the flange 12 of the stationary head may be shaped to provide an annular groove as 26 therein, and a split spring ring as 27 is suggested for gripping about the outer surface of the bellows cloth and holding said cloth pressed into the groove 26.

In order to make this joint entirely air

tight it is suggested further that a layer of wax or other appropriate material as 28 may be applied within the groove prior to the application of the bellows cloth thereto so that when the bellows cloth is pressed into the groove by means of the ring 27 said cloth will be caused to become embedded within the waxy material and thus made proof against the passage of air either into or out of the bellows.

The connection of the bellows with the movable head may be performed in identically the same manner if desired, as illustrated, and it will be seen that in this way the bellows may be efficiently assembled with minimum expenditure of time and effort.

It will be seen from the structure as thus far described that when the bellows is in the position as shown in Figs. 1 and 2 (that is when the doll within which the device is mounted is in its upright position) the bellows will stand normally collapsed but that when the device is reversed, as by movement of the doll, the movable head of the bellows will fall by gravity and distend the bellows as in Fig. 3 thus drawing air into the bellows through the reed for sounding the reed. The inward movement of air will however be controlled by opening and closing of the sound box closure 20.

While the closure 20 of course stands open, by gravity when the device is in the position Figs. 1 and 2, it will instantly close by gravity when the device is reversed. It will remain closed as long as the device stands reversed, except as it will be forced open by the sound control mechanism H which is now to be described.

The sound control mechanism H performs its function by controlling the position of the closure 20 according to a pre-arranged schedule. In the present instance it is designed for causing the sound to be emitted in such manner as to pronounce the word ma-ma and it accomplishes this by first opening the closure for a short period sufficient to permit of the emission of a short sound of the reed, corresponding with the syllable ma, then by permitting the closure to close by gravity for a momentary period sufficient to mark the separation between the first and second syllables of the word ma-ma, and finally by again opening the closure and holding it open for the prolonged sounding of the second syllable of the word.

This operation of the control mechanism is gravity controlled but without mechanical connection with the gravity moving bellows head. It occurs of course during the period while the bellows head is moving however but its phases have no precise relation or mechanical association with the position of the movable bellows head. The first syllable will be sounded during the early stages of movement of the bellows head and the second

5 syllable will be sounded during the latter stages of movement of the bellows head, and preferably the second syllable will be of longer duration than the first, but the relative lengths of these syllables will depend largely upon the manner and the rapidity of movement of the doll.

10 The control mechanism H as illustrated consists of two discs, as 29 and 30, mounted to oscillate freely upon a common pivot as 31 which projects laterally from a carrier plate 32, the latter being rigidly connected with the partition G and extending therefrom longitudinally of the housing in substantially 15 parallel relation to the path of movement of the movable head of the bellows so that the pivot 31 is arranged axially transverse to the path of the bellows head.

20 A separator as 33 is arranged between these discs in order that there may be no frictional influence of one upon the other.

25 The disc 29 has a radially projecting finger as 34 which is positioned for wiping against the surface 23 of the closure as the disc rotates, this wiping engagement being of a character to cause the closure to be opened and then closed as the finger engages and passes the surface.

30 The disc 29 also has a stop pin as 35 thereon positioned to engage a shoulder or other appropriate form of stop as 36 stationary with the plate 32 to limit movement of the disc in one direction, movement in the opposite direction being limited by engagement of the finger 34 with a second stop as 37 also rigid with the plate 32.

35 The disc 29 is so weighted that when the device is in the position as in Figs. 1 and 2 the disc will stand normally with its finger 34 resting against stop 37 and so that when the device is reversed the disc will swing by gravity, through the position as indicated in Fig. 4 and to the position as indicated in Fig. 3, thus causing the finger 34 to wipe across the surface 23 and the stop 35 to come to rest against the stop 36.

40 The disc 30 has a radially projecting finger as 38 which is positioned for wiping against the cam 24 of the closure as the disc 30 rotates. This wiping engagement is of a character to cause the closure to be opened and held opened as the finger engages the cam and continues to stand in engagement therewith, as shown in Fig. 3.

45 The disc 30 also has a stop pin 39 thereon positioned to engage a shoulder as 40 which is provided for the purpose upon the disc 29 to limit movement of the disc 30 in one direction as in Fig. 3, movement of said disc 30 in the opposite direction being limited by engagement of the stop pin 39 with a stop or shoulder as 41 rigid with the plate 32, as in Fig. 1.

50 The disc 30 is so weighted that when the device is in the position as in Figs. 1 and 2

55 said disc 30 will stand normally with its stop pin 39 resting against the shoulder 41, with the finger 38 spaced a considerable distance from the cam 24, and so that when the device is reversed said disc 30 will maintain its position unaltered as in Fig. 4 until the pin 35 60 of disc 29, during its movement as above referred to, strikes the finger 38 and thereby gives impetus to the disc 30 sufficient to carry it over a dead centre and thereafter cause it to function by gravity for swinging the finger 38 through the intervening space to and against the cam 24 for lifting the sound box closure, as in Fig. 3.

65 It will be seen that the period of time during which the sound box closure is initially open for the pronunciation of the first syllable of the word ma-ma is determined by the period of engagement of finger 34 with the surface 23 and that this may be modified within desirable limits by the speed 70 of movement of the finger and the shape of the surface 23 with respect to the path of movement of said finger. Also that the period of time between the closing of the sound box closure by the passing of finger 34 and its subsequent opening by finger 38 is of duration dependent upon the distance 75 through which the finger 38 moves and its speed of movement. And further that the duration of time for the sounding of the final 80 syllable of the word ma-ma is quite indefinite and is limited only by the duration of opening movement of the bellows after 85 the sound box closure has been opened by 90 the finger 38.

95 It is a matter of importance to note that the stationary plate 32 not only serves as a support for the moving elements of the sound control mechanism but also stands as a partition longitudinally of the housing L dividing 100 said housing into two compartments one as 42 for containing the bellows and the other as 43 for containing the sound control mechanism. It co-operates also with the walls of 105 the housing to constitute a suitable guide for the movable head of the bellows.

110 The cam 24 is so shaped and related to the finger 38 that when the parts are in the position Fig. 3 the finger 38 will be caught behind a relatively high point or hump of the cam and thereby held by friction against any 115 rebound movement away from the cam.

120 As many changes could be made in this construction without departing from the scope of the invention as defined in the following claims, it is intended that all matter contained in the above description or shown in the accompanying drawings, shall be interpreted as illustrative only and not in a 125 limiting sense.

130 Having thus described my invention, what I claim as new and desire to secure by Letters Patent is:—

1. A sound producing device comprising a

casing, a reed within said casing, means also within the casing for sounding the reed comprising a member movable by gravity in one direction along the casing, means providing a sound chamber with which the reed communicates and having a sound emitting opening therefrom, a closure for said opening, means constituting a partition within the casing extending parallel with the path of movement of said gravity movable member and at one side thereof, and control means for said closure arranged within the casing at the opposite side of said partition.

2. A sound producing device comprising a casing, a reed within said casing, means also within the casing for sounding the reed comprising a member movable by gravity in one direction along the casing, means providing a sound chamber with which the reed communicates and having a sound emitting opening therefrom, a closure for said opening, means constituting a partition within the casing extending parallel with the path of movement of said gravity movable member and at one side thereof, and control means for said closure arranged within the casing at the opposite side of said partition, said control means comprising a gravity control element the gravity movement of which is in the same general direction as the gravity movement of the first mentioned gravity movable member.

3. A sound producing device comprising a casing, a reed within said casing, means also within the casing for sounding the reed comprising a member movable by gravity in one direction along the casing, means providing a sound chamber with which the reed communicates and having a sound emitting opening therefrom, a closure for said opening, means constituting a partition within the casing extending parallel with the path of movement of said gravity movable member and at one side thereof, control means for said closure arranged within the casing at the opposite side of said partition, said control means comprising a pair of pivotally mounted members having weighted portions to move by gravity in the same general direction as said first mentioned gravity movable member for thereby rotating said members, and said members having portions to engage the closure.

4. A sound producing device comprising a casing, a reed within said casing, means also within the casing for sounding the reed comprising a member movable by gravity in one direction along the casing, means providing a sound chamber with which the reed communicates and having a sound emitting opening therefrom, a closure for said opening, means constituting a partition within the casing extending parallel with the path of movement of said gravity movable member at one side thereof, control means for said closure arranged within the casing at the opposite

side of said partition, said control means comprising a pair of members pivotally supported upon said partition, said members having weighted portions to move by gravity in the same general direction as said first mentioned gravity movable member for thereby rotating said members, means whereby the rotation of one member is consequent upon rotation of the other, and said members each having a portion to engage the closure to open the closure during rotation of the respective members.

5. A sound producing device comprising a casing, means providing a partition extending across the casing in fixed relation thereto having a sound chamber provided therein, a reed communicating with said chamber, means connected with said partition co-operative therewith to provide a bellows in communication with the reed to sound the reed by operation of the bellows, said bellows having a gravity movable head, the sound chamber having a sound emitting opening through one wall thereof, a closure for said opening, and control means for said closure arranged within the casing at one side of the bellows forming means, said control means comprising a part having operative connection with the closure to control the closure and being disconnected operatively from the movable head of the bellows.

6. A sound producing device comprising a casing, means providing a sound chamber therein, a reed communicating with said sound chamber, means providing a bellows in communication with the reed including a movable head adapted to travel by gravity longitudinally of the casing for thereby causing a flow of air through the reed to sound the reed, the sound chamber forming means having a sound emitting opening therefrom, a pivotally mounted closure for said opening having portions at its free edge adapted to be engaged by actuating elements of a control mechanism for said closure, together with a control mechanism for said closure disposed within the casing at one side of the bellows comprising gravity controlled parts engaging the mentioned portions of the closure to actuate the closure.

7. A sound producing device comprising a reed, means to sound the reed, and means to interrupt the sound produced by the reed comprising a movable sound controlling member and a pair of discs pivotally mounted adjacent said sound controlling member having portions to engage said member during rotary movement of the discs, and means whereby the rotary movement of one disc is consequent upon rotary movement of the other.

8. A sound producing device comprising a reed, means to sound the reed, and means to interrupt the sound produced by the reed comprising a movable sound controlling member and a pair of discs pivotally mounted ad-

5 jacent said sound controlling member having portions to engage said member during rotary movement of the discs, and means whereby rotary movement of one disc to move the sound controlling member will effect a rotary movement of the second disc for again moving the sound controlling member.

In testimony whereof I affix my signature.
FRED I. LAUTER.
